ANCHORAGE MEANS FOR TRACK RAILS AND THE LIKE

Filed June 30, 1930

UNITED STATES PATENT OFFICE

PAUL CHIPMAN, OF DETROIT, MICHIGAN, ASSIGNOR OF ONE-HALF TO FRANK H.
ALFRED, OF DETROIT, MICHIGAN

ANCHORAGE MEANS FOR TRACK RAILS AND THE LIKE

Application filed June 30, 1930. Serial No. 465,039.

This invention relates generally to means for fastening or anchoring track rails upon suitable supports.

One of the essential objects of the invention is to provide simple and efficient means of this type capable of effectively holding rails upon concrete roadbeds such as those illustrated in United States Patents Nos. 1,716,911 and 1,754,609.

Another object is to provide a fastening means which permits both lateral and vertical adjustments and enables the rails to be fastened upon almost any form of seat or bed.

Another object is to provide means auxiliary to the fastening means just mentioned and operable automatically when loads are placed on the rails to take up play between the rails and the fastening means so that the rails will be held tightly upon their supports.

Other objects, advantages, and novel details of construction of this invention will be made more apparent as this description proceeds, especially when considered in connection with the accompanying drawings, wherein:

Figure 1 is a cross sectional view through a concrete roadbed and showing rail anchorage means embodying my invention applied thereto;

Figure 2 is an enlarged fragmentary vertical sectional view through the roadbed and one of the rails;

Figure 3 is an elevation of one of the stirrup sections;

Figure 4 is a detail view of one of the clamping members;

Figure 5 is a view taken at right angles to Figure 4;

Figure 6 is a view similar to Figure 2 and showing a slight modification.

Referring now to the drawing, 1 is a roadbed; 2 and 2' respectively are laterally spaced rails on the bed; 3 are boards set in the bed beneath the rails; 4 and 5 respectively are stirrup sections embedded in the concrete upon opposite sides of the rails and having inwardly inclined portions 6 and 7 respectively above the concrete provided with threaded openings 8 and 9 respectively; 10

and 11 respectively are steel castings adapted to be clamped upon the bases 12 of the rails; and 13 and 14 respectively are set screws threadedly engaging the openings 8 and 9 in the inclined portions 6 and 7 respectively of the stirrup sections and constituting followers for the castings 10 and 11 so that the rail bases 12 may be clamped upon the bed 1. As shown, the castings 10 and 11 are identical in construction. Each preferably has a transversely extending substantially L-shaped recess 15 in one side and is provided in its other side with a longitudinally extending channel shaped recess 16. When assembled the long sides 17 of the L recesses 15 incline downwardly and outwardly and engage the inclined top faces 18 of the rail bases, while the short sides 19 of said recesses are vertically disposed and engage opposite edges of the rail bases. The channels 16 are inclined relative to the bed and receive the inner ends of the screws 13 and 14. In fact, the bases 20 and 21 respectively of the channels are substantially parallel to the inclined portions 6 and 7; hence are at right angles to and provide firm bearings or abutments for the screws 13 and 14.

With this construction the screws 13 and 14 may be loosened to permit both lateral and vertical adjustments of the rails 2 relative to the bed 1 and may be easily and quickly tightened to hold the rails in adjusted position on the bed.

In the present instance wedges 22 are provided to take up play between the screws and castings. For instance, when a load such as a train is on the rails, the bases 12 and castings 10 and 11 move downwardly slightly relative to the screws 13 and 14. Thus spaces are momentarily provided between the bases 20 and 21 of the recesses 16 and the inner ends of the screws 13 and 14, and successive movements of the rails and castings 10 and 11 in this manner would have a tendency to loosen the connections. Hence, the wedges 22 are used to take up such play. In use these wedges are positioned in the channel recesses 16 between the bases thereof and the inner ends of the screws so that they may slide down by gravity in the recesses when spaces

are provided therefor as a result of loads being placed upon the rails. Thus the wedges automatically maintain tight connections between the parts.

5 In Figure 6 I have illustrated a slight modification in which the stirrup sections 30 and 31 are integral. Otherwise the construction is the same as that illustrated in Figures 1 to 6 inclusive.

10 While it is believed that from the foregoing description the nature and advantages of the invention will be readily apparent, I desire to have it understood that I do not limit myself to what is herein shown and 15 described and that such changes may be resorted to when desired as fall within the scope of what is claimed.

What I claim as my invention is:

1. The combination with a rail of a track, 20 and a support therefor, of means for anchoring the rail upon the support, including clamping members engaging opposite edges of the base of the rail, anchorage members rigid with the support upon opposite sides 25 of the rail, and followers for said clamping members carried by said anchorage members.

2. Means for anchoring a rail of a track upon a suitable support including a stirrup section adapted to be secured to the support 30 and having an inclined portion, a screw threadedly engaging the inclined portion, and a clamping member free with respect to the screw and having slots respectively receiving a portion of the rail and an end of the screw.

35 3. Means for anchoring a rail of a track upon a suitable support including a casting having a slot for receiving an edge of a rail and having another slot, a member attachable to the support having an inclined portion substantially parallel to the base of the second-mentioned slot, and a set screw extending through the inclined portion and having the end thereof engageable with the base of the second-mentioned slot in the casting.

40 4. The combination with a concrete roadbed and a rail on said bed, of means for securing the rail upon the bed including a member embedded in the bed and provided above the bed with an inclined portion, a clamping member having portions engaging the top face and an edge of the rail base, and a follower for the clamping member adjustable in the inclined portion aforesaid of said member.

45 5. Means for anchoring a rail of a track upon a suitable support including a member rigid with the support at one side of the rail, 50 a clamping member engaging the rail, a follower for the clamping member carried by the first mentioned member, and means between the follower and last mentioned member operable automatically to take up play 55 between said parts to insure a tight con-

nnection between the clamping member and rail.

6. Means for anchoring a rail of a track upon a suitable support including a clamping member engageable with the base of the rail, a follower for the clamping member, a support for the follower rigid with the rail support, and means associated with the clamping member and follower for automatically taking up play therebetween to insure 70 a tight connection between the clamping member and rail.

7. The combination with a concrete roadbed and a rail on said bed, of means for securing the rail upon the bed including upright 80 members embedded in the bed and provided above the bed with inclined portions, clamping members engaging opposite edges of the rail, and followers for said clamping members adjustable transversely of the inclined 85 portions of the upright members aforesaid.

8. The combination with a rail of a track, and a support for said rail, of means for anchoring the rail upon the support including upright members rigid with the support and disposed upon opposite sides of the rail, said upright members being provided above the base of the rail with inclined portions, clamping members engaging opposite edges of the base of said rail, followers for the clamping members adjustable in the inclined portions aforesaid, and removable means associated with said clamping members and followers for automatically taking up play therebetween to insure tight connections 90 between the clamping members and the rail.

In testimony whereof I affix my signature.

PAUL CHIPMAN.
